UNITED STATES PATENT OFFICE.

NICOLAI H. HILLER, OF CARBONDALE, PENNSYLVANIA.

COMPRESSOR.

Application filed January 15, 1923. Serial No. 612,583.

To all whom it may concern:

Be it known that I, NICOLAI H. HILLER, a citizen of the United States, and resident of Carbondale, in the county of Lackawanna and State of Pennsylvania, have invented certain new and useful Improvements in Compressors, of which the following is a specification.

This invention is an improvement in gas compressors and relates particularly to the intake or suction pipe connections, the main objects being to permit of the use of a smaller suction pipe, avoid pulsation of the gas in the suction pipe, prevent the passage of liquid to the cylinder, and avoid the necessity for gauze strainers to prevent scale, dirt or other solid matter from passing into the intake valves or cylinder.

In carrying out my invention I provide a receiver or chamber closely adjacent to the compressor and connected to the compression chambers by separate open-ended nipples terminating materially above the bottom or lower wall of the receiver. The receiver is preferably of a capacity in excess of the capacity of one of the compression chambers, and the suction pipe to the receiver enters at such a point that liquid or solid particles are deposited in the receiver before passing to said intake nipples.

In the accompanying drawings I have illustrated my invention as applied to both a double acting and a single acting compressor.

In these drawings:

Fig. 1 is a side elevation of a double-acting compressor provided with my improved construction, certain of the parts being shown in section.

Fig. 2 is an end view partly in section.

Fig. 3 is a front elevation showing my construction attached to a compressor having a pair of single acting cylinders, and

Fig. 4 is a side elevation of Fig. 3.

In Figs. 1 and 2 I have illustrated my invention as applied to a compressor having a horizontally disposed cylinder 10 of the double acting type and provided with intakes 11 at opposite ends thereof, and a piston 12. Instead of connecting the suction pipe to the intakes by the usual form of manifold, I provide a receiver or chamber 13 preferably of a capacity substantially equal to one and one-half times the capacity of the cylinder 10, and supported by a pair of projecting open-ended nipples 14 preferably directly secured to the cylinder at the intake there-

of. The receiver 13 is mounted comparatively close to the cylinder, and the nipples 14 extend into the receiver to a point materially above the middle of the latter. The receiver 60 intermediate of the two nipples 14, is provided with an intake 15, and a suitable coupling 16, for direct connection to the suction pipe. This intake 15 thus comes preferably below the upper open ends of the 65 nipples 14.

The compressor in operation draws first through one nipple and then through the other, but these nipples are of such short length that little or no pulsation of the gas 70 takes place within them. The velocity of the gas entering the receiver at the intake 15 drops by reason of the larger capacity of the receiver rather than directly from the suction line, so that the pulsation is not 75 transmitted back to the suction line. Thus there will be a steady and uniform flow through the suction pipe. By preventing pulsation in the suction pipe a very much smaller pipe may be employed, and still the 80 proper filling of the cylinder on each piston stroke is insured. Due to the drop in velocity of the gas as it enters the receiver, particles of scale, dirt or other solid matter will separate out and collect in the receiver, 85 and due to the position of the inlet ends of the nipples, such solid matter will not be carried into the cylinder. Also any liquid which may be carried along by the gas will separate out in the receiver, and may be 90 drawn off from the receiver when necessary by means of a small drain cock 17. The separation of liquid from the gas is particularly important when the compressor is used as the ammonia compressor of a refrigerating sys- 95 tem, as particles of liquid ammonia carried into the compressor often cause trouble by reason of the low temperature and the water hammer effect. Furthermore the construction eliminates the necessity of a suction 100 strainer of fine gauze which is ordinarily necessary and which offers material resistance to the free flow of the gas. As the receiver is not in direct contact with the cylinder, the gas in the receiver is not heated by 105 heat of the cylinder.

In Figs. 3 and 4 I have shown the same type of intake receiver and connections for two compression chambers which are in separate cylinders 10^a of the single acting type 110 instead of at opposite ends of a single cylinder of the double acting type. The cylinders

are shown as vertically disposed rather than horizontally disposed, and the nipples 14^a are of elbow form.

As the invention relates primarily to the intake construction, I have not illustrated the outlet and other mechanical details of the compressor.

Having thus described my invention, what I claim as new and desire to secure by Letter Patent is:

1. A compressor having a plurality of compression chambers provided with separate intakes, a chamber disposed closely adjacent to said compressor, separate nipples extending from said intakes into said chamber, and terminating above the bottom of the latter, and an intake to said chamber.
2. A compressor having a plurality of compression chambers each provided with an intake, a chamber disposed closely adjacent to said compressor, separate nipples extending from said intakes into said chamber and terminating above the bottom of the latter, and an intake to said chamber at a point intermediate to said nipples.
3. A compressor having a plurality of compression chambers each provided with an intake, a chamber disposed closely adjacent to said compression chambers, separate nipples extending from said intakes into said chamber and terminating above the bottom of the latter, and an intake to said chamber, said receiver being of a capacity at least equal to that of the capacity of one of said compression chambers.
4. A gas supply connection for a multiple chambered compressor, including a receiver of a capacity in excess of the capacity of a compression chamber, a pair of comparatively short intake nipples projecting

into said receiver and adapted to be connected to the compressor intakes, and a suction pipe connection to said receiver.

5. A gas supply connection for a multiple chambered compressor including a chamber of a capacity in excess of the capacity of the compressor cylinder, a pair of comparatively short intake nipples projecting into said chamber and adapted to be connected to the compressor intakes, and a suction pipe connection to said chamber intermediate of said nipples and below the upper ends thereof.

6. A gas supply connection for compressors, including a chamber of a capacity in excess of the capacity of the compressor, a pair of comparatively short intake nipples projecting into said chamber and adapted to be connected to the compressor intakes, a suction pipe connection to said chamber, and a liquid drain at the lower side of said chamber.

7. In combination, a substantially horizontally disposed double acting compressor having intakes at the upper side thereof at opposite ends, a receiver extending substantially parallel to said cylinder directly above the same, a pair of comparatively short intake nipples extending from the cylinder intakes and supported by the cylinder and serving to support said receiver, said intakes extending upwardly into the receiver to points materially above the bottom of the latter, and a suction pipe connection to said receiver intermediate of said nipples.

Signed at Carbondale, in the county of Lackawanna and State of Pennsylvania, this 12th day of January, A. D. 1923.

NICOLAI H. HILLER.
